[57] **CLAIM**

The ornamental design for a modular building system eave connector, as shown and described.

DESCRIPTION

FIG. 1 is a perspective environmental view of a modular building system eave connector;

FIG. 2 is a perspective environmental view of the modular building system eave connector in a steep pitch configuration;

FIG. 3 is an enlarged isometric view thereof;

FIG. 4 is a top plan view thereof;

FIG. 5 is a front elevational view thereof;

FIG. 6 is a rear elevational view thereof;

FIG. 7 is a bottom plan view thereof; and,

FIG. 8 is an end elevational view thereof, the opposite end being a mirror image thereof.

The broken line showing of a rafter, column and fasteners in FIGS. 1 and 2 is for illustrative purposes only and forms no part of claimed design.
